ION SOURCE

Clifford E. Berry, Altadena, Calif., assignor to
Consolidated Engineering Corporation, Pasadena, Calif., a corporation of California

Application October 27, 1952, Serial No. 317,106

9 Claims. (Cl. 250—41.9)

1

This invention is directed to an ion source characterized by development of a high intensity ion beam. The ion source finds use in mass spectrometry, ionization gauges, ionic vacuum pumps and the like.

In the presently conventional form of ion source, ions are developed by electron bombardment of an ionizable medium. Usually an electron beam is directed across an ionizing region from an electron source or gun adjacent one side of the region to an electron target adjacent an opposite side. The electrons traversing the region are discharged at the target. The electron beam in such instance traverses the ionizing region once only.

As the pressure of an ionizable gas in the ionization region is reduced, the probability of an electron striking a gas particle decreases linearly. As a consequence at very low pressures, to which ion sources are generally exposed, very few electrons make an ionizing collision. By way of example, in nitrogen at a pressure of 10^{-6} mm. Hg the mean free path of an electron is about 300 meters, while the path of an electron in a typical ion source is approximately 3 cm. Therefore, on the average, only one electron in 10,000 will make an ionizing collision.

To increase the efficiency of ionization it is necessary to increase the probability of ionizing collisions. This end may be achieved at any given pressure only by increasing the intensity of the electron beam or by increasing the distance that each electron travels in the ionizing region. But there are practical limitations on the extent to which the intensity of an electron beam can be increased as determined by power consumption, filament size, overheating, and the like. By increasing the length of the path of an electron in an ionizing region the probability of any given electron striking a gas molecule is increased accordingly, and the same net result is accomplished as would be possible from a corresponding multiplication of electron intensity.

I have developed an ion source such that each electron may traverse the region of ionization many times. An ion source in accordance with the invention comprises means defining an annular ionization chamber, a magnet shaped to develop a radial magnetic field across the chamber, an electron emitting filament disposed concentrically with respect to the chamber adjacent either the outer or inner circumference of the annulus, means for directing the electrons emitted from the filament radially across the chamber, means disposed in the plane of the filament and on the opposite side of the annular chamber for redirecting such electrons radially back toward the filament, and means expelling ions from the ionization chamber.

2

In this type of ion source electrons travel back and forth between the filament and the means for redirecting the electrons, the energy of the electrons being insufficient to enable them to strike either the filament or the redirecting means. As a consequence, the electrons gradually circumscribe the annulus traveling approximately radially back and forth across the chamber in the process of migration around the chamber.

The invention will be clearly understood with reference to the following detailed description taken in conjunction with the accompanying drawing, in which:

15 Fig. 1 is a front elevation of an ion source in accordance with the invention;

Fig. 2 is a vertical section taken on the line 2—2 of Fig. 1; and

20 Fig. 3 is a partial vertical section through an evacuating system including an ionic vacuum pump embodying the invention.

The ion source illustrated in Figs. 1 and 2 comprises a cylindrical magnet 10 having a central coaxial core 11 and defining an annulus 12 across which a radial magnetic field is developed by the magnet. An annular metal shell 14 is supported within the annulus 12 by insulating posts 15 connected between the magnet 10 and shell 14. The shell is provided with co-planar inner and 25 outer circumferential slots 18, 19, respectively, which are continuous save for a minimum number of structural webs 20.

An electron emitting filament 22 of generally 30 circular configuration is mounted concentrically around magnet core 11 interiorly of the annulus shell 14 and in the plane of the co-planar slots 18, 19. The filament 22 is discontinuous and adjoining ends thereof are connected by leads 35 23, 24 across a power source 25. Conventionally, the leads 23, 24 are constructed in the form of 35 support posts to support the filament within the magnet. A cylindrical electron reflector 28 is mounted in the annulus 12 exteriorly of the shell 14 and is supported therein by insulating

40 posts 29 extending from the magnet, the arrangement being such that the electron filament 22, the inner and outer peripheral slots 18 and 19 of the shell 14 and the cylindrical reflector 28 are in a common radial plane. Electrons emitted 45 from filament 22 may pass successively through slots 18 and 19 and approach reflector 28 outwardly of shell 14.

A grid 30 is disposed adjacent the open outer 50 face of shell 14 and is supported in this position by an insulating post 31. The grid 30 may be a helical coil, as shown, separate concentrically arranged circular conductors, or an annular screen, the function of the grid being de-scribed hereinafter.

55 The ion source is adapted to be mounted within

an envelope 34 which may, for example, form a part of a mass spectrometer system and includes an exhaust line 35 adapted to be connected to an evacuating system (not shown) and a gas inlet line 36 for admitting into the system a gas to be ionized.

Filament 22 is biased negatively with respect to the shell 14 by means of a potential source 38 and at the same time is biased positively with respect to the reflector 28 by means of a potential source 39. The grid 30 is biased negatively with respect to the shell 14 by means of a potential source 40, the effect of the relative potentials of the several elements being made apparent from the following description of the operation of the 15 ion source.

Electrons are emitted from filament 22 and, under the influence of the potential existing between the filament and the shell 14, are propelled through the shell slit 18 and travel radially across 20 the annulus defined by the shell. The radial magnetic field has the effect of constraining the electrons very nearly in the plane of the filament so that in traveling across the ionization chamber they are directed toward the outer peripheral slit 19 thereof and approach the reflector 28. However, because of the combined action of the magnetic field and the electrical field between the shell and the grid 30, the electrons undergo an 25 angular deflection in the plane of the filament. After passing through the outer peripheral slit 19 they are reflected back into the chamber as a consequence of the repelling potential developed between the reflector 28 and the shell. Again such 30 a reflected electron will undergo a further angular deflection in the same direction and in the same plane. If the filament is operated on direct current and the polarity is correctly established, a given electron returning to the filament after traveling across the ionization chamber and back inherently approaches a point on the filament 35 more negative than that from which it was emitted so that it is again reflected. As a consequence, any given electron will tend to make repeated traversals of the annulus defined by the shell 14 while at the same time migrating around the axis of the shell in a direction toward the negative terminal of the electron filament 22.

As ions are formed within the annulus defined by shell 14 they are expelled therefrom under the influence of the propelling potential between shell 14 and grid 30. The resulting beam is of annular section as defined by the radial section of shell 14 and is propelled from the shell in a direction paralleling the longitudinal axis thereof.

A characteristic electron path is plotted in part in Fig. 1 as the dotted line 42. Each time an electron traverses the annular ionizing region in excess of its first crossing, the effect is the same as a like multiplication of the intensity of electron emission at the filament. Thus, in a conventional ion source, many times the normal power requirement would be required to develop an ion beam of an intensity corresponding to that produced in the present ion source by multiple-stage electron traversal of the ionizing region. Actually, a given electron, unless undergoing an ionizing collision, will traverse the ionizing region many hundreds of times.

The same operation is effectuated if the electron emitting filament and the reflector interchange in relative position. It is, however, preferable to mount the filament inwardly of the annular ionizing region, as shown, as minimizing power requirements and heating effects.

The ion source shown in Figs. 1 and 2 is adapted for use in a mass spectrometer and particularly a mass spectrometer of a type which does not operate on a sharply defined ion beam. The comparatively recently developed high frequency mass spectrometers are representative of the type of instrument in which the present ion source is of great value. The ion source is similarly ideally suited for use in an ionization gauge.

The use of an ion source in accordance with the invention as an ionic vacuum pump in an evacuating system, is illustrated in partial sectional elevation in Fig. 3. The source shown in this figure is identical to that above described and component parts thereof are identified by like reference characters. The source is disposed at an end of a comparatively long tube 50 adapted to connection to a system to be evacuated identified by the reference character 52, the source being interposed between the tube and system with space for gas flow or diffusion from one to the other. The opposite end of the tube 50 is connected serially to a conventional diffusion pump 54 and a fore-pump 56.

The principle of operation of an ionic vacuum pump is well known in the art and the advantages attendant upon the utilization of a high intensity ion beam therein are consequently readily apparent. The various elements of the ion source are maintained at the relative potentials as described in relation to Fig. 2 and in addition the elongated tube 50 of the pump is maintained at a negative potential with respect to grid 30 by means of a potential source 58.

In operation, gas molecules migrating into the annular ionizing region of the source as defined by the shell 14 are ionized and propelled under the influence of the propelling potential between the shell and the grid 30 along the tube 50. The ions are discharged at an end wall 50A of the tube and the resultant neutral particles diffuse both back along the tube 50 and in the direction of diffusion pump 54. Since the tube 50 is purposely made long in comparison with the diffusion pump connection, the majority of the thus neutralized particles find their way out of the system through the diffusion pump.

I claim:

1. An ion source comprising means defining an annular ionization chamber, means developing a radially directed magnetic field across the chamber, an electron emitting filament disposed concentrically with respect to the chamber, means directing electrons emitted from the filament radially across the chamber, means redirecting such electrons radially back toward the filament, and means expelling ions from the ionization chamber.

2. An ion source comprising a metal shell defining an annular ionization chamber, the shell having substantially continuous and radial aligned slots in its inner and outer cylindrical walls, magnet means developing a radially directed magnetic field across the chamber, an electron emitting filament disposed concentrically with respect to the shell and exteriorly of the annulus defined thereby, means directing electrons emitted from the filament radially across the chamber through the radially aligned slots, means redirecting such electrons radially back toward the filament, and means expelling ions from the ionization chamber.

3. Apparatus according to claim 2 wherein said magnet means comprises a cylindrical magnet member closed at one end and having an axial

core defining an annulus with the cylindrical magnet wall in which said shell is mounted.

4. An ion source comprising a metal shell defining an annular ionization chamber, magnet means developing a radially directed magnetic field across the chamber, an electron emitting filament disposed concentrically with respect to the shell, means directing electrons emitted from the filament radially across the chamber, a cylindrical reflector disposed concentrically with respect to the shell and opposite the filament for reflecting electrons radially back toward the filament, and means expelling ions from the ionization chamber.

5. Apparatus according to claim 4 wherein said filament comprises a broken ring, the two adjacent ends thereof being adapted to connection across a voltage source.

6. An ion source comprising a metal shell open at one face and defining an annular ionization chamber, magnet means developing a radially directed magnetic field across the chamber, an electron emitting filament disposed concentrically with respect to the shell, means directing electrons emitted from the filament radially across the chamber, a cylindrical reflector disposed concentrically with respect to the shell opposite the filament for reflecting electrons radially back toward the filament, a conductive grid disposed adjacent the open face of the shell, and means maintaining the grid at a negative potential with respect to the shell.

7. Apparatus according to claim 6 including means maintaining the shell at a positive potential with respect to the filament and the re-

10
15

35

flector at a negative potential with respect to the filament.

8. An ion source comprising a generally cylindrical magnet structure closed at one end and having an axial core extending inwardly from the closed end to define an annulus between the core and cylindrical wall across which a radial magnetic field is maintained, a metal shell mounted in said annulus and comprising inner and outer cylindrical wall portions joined concentrically by an annular closure member extending between radially aligned ends of said wall portions, each wall portion having a substantially continuous circumferential slot therein with the two slots being in radial alignment, an electron emitting filament mounted concentrically with and exteriorly of the shell in radial alignment with an adjacent one of said slots, a cylindrical conductive reflector mounted concentrically with and exteriorly of the shell in radial alignment with and adjacent the other of said slots, a conductive grid disposed adjacent the end of the shell opposite said closure member, a voltage source connected to the filament, and means biasing the filament, shell, reflector and grid so that the shell is at a positive potential with respect to the filament.

9. Apparatus according to claim 8 wherein the filament is mounted concentrically around the magnet core between the core and inner wall member of the shell, and the reflector is mounted concentrically around the shell between the shell and cylindrical magnet wall.
